UNITED STATES PATENT OFFICE.

THOMAS H. MURPHY, OF BROOKLYN, NEW YORK.

TAR, SAND, AND ASPHALT MIXER.

1,405,543.

Specification of Letters Patent. Patented Feb. 7, 1922.

Application filed June 25, 1920. Serial No. 391,639.

To all whom it may concern:

Be it known that I, THOMAS H. MURPHY, a citizen of the United States, residing at Brooklyn, in the county of Kings and State 5 of New York, have invented certain new and useful Improvements in Tar, Sand, and Asphalt Mixers, of which the following is a specification.

This invention has relation to new and 10 useful improvements in agitators and more particularly to a machine designed as a tar, asphalt and sand mixer to be used in connection with the paving of streets and particularly for falling in between paving 15 blocks to fill up crevices and cause the adhesive of adjacent blocks to prevent them from becoming loose or displaced.

An object of the invention is to provide a 20 machine embodying means for delivering from a source of supply any desired quantity of tar, asphalt or the like in a molten state, to a mixing device embodying means for incorporating the substance with any suitable proportion of sand, gravel or the 25 like, and for maintaining constant the temperature of the mixture.

Another object of the invention is to provide a machine embodying the characteristics above named and including in addition 30 thereto means for generating steam and for circulating the same around the mixing device for maintaining the temperature of its contents.

In addition to the foregoing this invention 35 comprehends improvements in the details of construction and arrangement on parts to be hereinafter described and particularly set forth in the appended claims.

In the accompanying drawing the figure 40 is a view in longitudinal section, partly in elevation of a mixing machine constructed in accordance with my invention.

With reference to the drawings, 10 indicates a truck having supported thereupon an 45 inverted frusto-conical container indicated at 11. The upper end is open, but normally closed by means of a removable cover 12. A support 13 is extended diametrically across the upper end of the container to form a 50 journal for a vertical shaft 14 located centrally of the container, the lower end of the shaft passing through a bearing in the bottom of the container and supported upon a thrust bearing 15 mounted upon the truck. 55 Mounted upon the shaft 14 within the container is a plurality of blades 16 having

their outer edges formed parallel with the sides of the container and adjacent blades located at right angles. Each blade is furthermore provided with a central opening 60 17 to facilitate the agitation of the contents of the container. Mounted upon the lower end of the shaft 14 exteriorly of the container is a bevel gear 18 in meshing engagement with a similar gear 19 mounted upon a horizontal shaft 20. Said shaft is suitably journaled and provided at one end with a member 21 on a clutch, the other member being indicated at 22. The member 21 is shifted by means of a lever 23 to engage or 65 disengage the clutch. The member 22 of the clutch is suitably journaled for rotation and provided with a spur gear 24, the latter meshing with a pinion 25 mounted upon the fly wheel of an internal combustion engine 26. A second shaft 27 is provided having a gear 28 in meshing engagement with the pinion 25. The shaft 27 also carries fast and loose pulleys 27a.

Supported upon the truck is a fire box 29 80 containing a grate upon which fuel may be burned or a gasoline torch supported and having a flue 30 connected to its upper portion. The upper end of the fire box is open 85 to receive a boiler 31 therein, the latter being in the nature of a cast iron box having its upper end open and its lower portion extending into the fire-box. A support 32 extends across the upper end of the boiler 31 upon which a rotary pump 33 is supported,

the latter having a shaft 34 connected with the rotating part, said shaft carrying a pulley 35. A belt 36 is trained around said pulley 35 and around one or the other of the pulleys, the belt being shiftable from 90 one or the other of said last mentioned pulleys by means of an ordinary belt shifting apparatus. The inlet of the pump is connected to a flexible hose 37 which may be entered into a tank of molten tar or 95 the like while the outlet of the pump is connected with a conduit 39 which enters the upper end of the container 11. A coil of pipe 40 is wound spirally around the exterior of the container 11 with the upper 100 end of the pipe connected to the upper end of the boiler 31, a valve 41 being provided at the lower end of the pipe 40 to permit water of condensation to be drained therefrom. It is also desirable that lagging be 105 applied to the outer surface of the container 11 as indicated at 42, the lagging being pref-

110

erably held in place by means of a layer of 55
foraminous material 43. A spout 44 is pro-
vided at the lower end of the container 11
whereby the contents may be drawn there-
from, and the spout is normally closed ad-
jacent its point of connection with the 60
container by means of a slidable closure 45. A
second closure 46 is provided to the lower
end of the spout, preferably in the nature of
10 a butterfly valve.

In operation, the prime mover 26 is started
and motion thereof is communicated through
the gears 24 and 25 to the shaft 20, thence
through the gears 18 and 19 to the shaft
15 14, rotating the blade. The cover 12 is
removed and a suitable quantity of sand,
gravel or other material poured into the
container. At the same time the hose 37 is
entered into a tank of molten tar, asphalt
20 or the like and the belt 36 shifted to the
fast pulley, so that the motion is communi-
cated to the pump 33, thus permitting the
latter to withdraw the tar, asphalt or the
like from the tank and to deliver the same
25 into the container 11. The motion of the
blades 16 will effectually incorporate these
materials one with another into a homo-
geneous mixture, which may be withdrawn
when desired by first shifting the slide 45,
30 and then rotating the valve 46. Thus, it
will be readily seen that by the use of this
machine the expense and loss of time in-
cidental to mixing these materials by hand
at one portion of the work and delivering
35 them by means of wheel-barrows or the
like to another portion of the work is elim-
inated, since the process of mixing the
material can be carried out continuously
by means of this machine and directly in
40 proximity to the point where the materials
are to be delivered. The present system
of mixing these materials is to draw the
tar and asphalt in a wheel-barrow shovel
in the sand and mix with a hoe; this does
45 not assemble the materials properly and
when dumped on the pavement there is all
sand in one place and tar in another. In this
way the pavement becomes coarse and un-
even and sunken below normal grade
50 through the lack of enough sand in the
joint filler. It will be seen that by the use
of this machine the expense and loss of time
incidental to mixing these materials by
hand is eliminated, and by permitting the

use of more sand a saving of tar and asphalt 55
is effected which is the largest item of cost
in the paving of streets not to mention the
assurance of a more durable job with a
consequent reduction in the cost of main-
tenance. Other uses and advantages will 60
readily occur to those familiar to the art
to which this invention appertains.

While I have illustrated and described
my invention with some degree of particu-
larity, I realize that in practice various 65
alterations therein may be made. I there-
fore reserve the right and privilege of
changing the form of the details of con-
struction or otherwise altering the arrange-
ment of the correlated parts without de- 70
parting from the spirit of the invention
or the scope of the appended claims.

Having thus described my invention what
I claim as new and desire to secure by
United States Letters Patent is:—

75 1. A mixing machine including in com-
bination a container, an agitating element
located therein, a pump, a connection be-
tween the pump and container, and a single
means for heating the container and for 80
heating the pump.

2. A mixing machine including in com-
bination a container, an agitating means
therein, a pump, a connection between the
pump and container, a coil surrounding the 85
container, a source of steam for supplying
the coil, and an enclosure for the pump to
permit the steam to be accessible thereto
to maintain the pump at a high temperature.

90 3. A mixing machine comprising in com-
bination a container, an agitating means
therein, a coil surrounding the container,
a fire-box, a boiler within the fire-box, the
upper end of the coil being connected to
said boiler.

95 4. A mixing machine comprising in com-
bination, a container, an agitating element
therein, a coil surrounding the element, a
fire-box, a boiler located in the fire-box open
at one end, the upper end of the coil being 100
connected to the boiler, a support within
the boiler, a pump mounted upon said sup-
port, a connection between the pump and
container, and a closure for the upper end
of the boiler also enclosing the pump.

105 In testimony whereof I affix my signature.

THOMAS H. MURPHY. [L. s.]
